UNITED STATES PATENT OFFICE.

MAX EMER, OF VIENNA, AUSTRIA-HUNGARY.

SAFE HAVING COIN-OPERATED LOCK.

971,366.

Specification of Letters Patent. Patented Sept. 27, 1910.

Application filed April 25, 1910. Serial No. 557,389.

To all whom it may concern:

Be it known that I, MAX EMER, a subject of the Austro-Hungarian Emperor, and residing at 35 Klostergrasse, Vienna XVIII, in the Empire of Austria-Hungary, have invented certain new and useful Improvements in Safes Having Coin-Operated Locks, of which the following is a specification.

This invention has for its object to provide an improved safe for keeping valuables in public institutions or the like, of the kind in which the safe can be locked only after insertion of a coin and the key cannot be removed from the keyhole, once the safe is opened.

The present improvements consist more particularly in the feature that the inserted coin is pressed by means of a part, such as a lever or the like, against a member which is supported in the open position of the lock bolt, partly by the lock bolt and partly by the wall of the safe, whereby the said member is moved out of the position in which it prevents the lock bolt from being shot, and by this movement permits of the safe being locked, the coin being thrown off by the movement of the bolt in the usual way. The said member may consist of one part or of several parts pivoted or hinged together. In the first case the member may either be pushed by the coin out of the line of support parallel to itself, or it may be hinged to the lock bolt or to the wall of the safe, so that the member is rocked on the axis of the hinge by the coin out of the supporting line of support. In the second case it is preferred to connect the member to the bolt as well as to the wall of the safe by means of hinges, the parts of the member being rocked out of the line of support on the two hinges and on the central connecting hinges.

In the drawings:—Figure 1 is a sectional elevation of one modification of the improved safe. Fig. 2 is a cross section on the line A—A of Fig. 1; Fig. 3 is a longitudinal section on the line B—B of Fig. 1; and Fig. 4 is a cross section on the line C—C of Fig. 1; Fig. 5 is a section of the mechanism for stopping the lock bolt, shown in its inoperative position, Fig. 6 is a section of a modified construction of the mechanism for stopping the lock bolt, in one position, and Fig. 7 is the same section of the said mechanism showing the latter in a different position, and Fig. 8 is a section of a

further modification of the mechanism for stopping the lock bolt.

The safe consists of a back plate 1, which is adapted to be fastened to a wall or the like, and of a casing 3 adapted to rotate on a hinge-pin 2. The back plate 1 may however be connected to the sides to form the casing, and only the cover of the safe may be hinged. A compartment for receiving the automatic coin-receiving apparatus is formed in the casing 3 by means of a transverse partition 4 and a back wall 5, the case of the locking mechanism being formed by means of a longitudinal partition 6 and a back wall 7. The transverse partition 4 stops short of the bottom of the safe, so as to leave an aperture for the insertion of a money box into the compartment. Two catches 8 are pivoted on the back plate 1, and are adapted to engage by holes therein over knobs 9 on the casing 3, for the purpose of keeping the unlocked safe closed.

10 is a slot in the back wall 5 for the insertion of a coin, leading into a coin chute formed by two vertical partitions 11 and the horizontal arm 12' of a bell crank lever 12. The free end of the other arm 12² of the lever 12 is provided with a pin 13 projecting through an aperture in the wall 5, which comes in contact with the back plate 1 when the safe is closed and is thereby pushed inward, so that the lever 12 is turned against the action of a spring 14 and the lever arm 12' is raised. If desired, the coin slot 10 may be located in the front wall of the casing 3 and the pin 13 of the lever 12 may be arranged to project through an opening in the top of the safe. In such a case the lever will have to be actuated by pressure applied to the pin 13 by the finger of the user. When shot, the lock bolt 15 engages by means of its hooks 15' in the apertures of the lug 16 fixed to the back plate 1; it is constructed in a well known manner, such that when the lock is open the key 17 cannot be removed from the keyhole. The bolt 15 is provided with a lateral arm 18 which, in the construction shown in Fig. 3, consists of two parts 18' and 18², whereas in the construction shown in Figs. 6 and 8 it is formed in one piece. The two parts 18' and 18² (Figs. 1 and 3) are so combined that at the commencement of the movement of the lock bolt only the part 18' attached to same will move with it, while the other part 18²

will be moved only by the further movement of the lock bolt. For this purpose the part 18' is formed with a slot 18³, in which a pin 18⁴ of part 18² is adapted to slide.

5 20 (Figs. 1, 3, 5) is a member consisting of two parts connected together by a hinge 19; it is hinged at 21 to the arm 18 of the bolt 15. The other end of the member 20 is connected to a projection 22 on the wall 10 of the safe by a hinge 23. The hinges 21 and 23 permit of the parts of the member being turned upward, while the hinge 19 opens toward the opposite side. The member 20 is held extended by a spring 24 and thus prevents the locking movement of the lock bolt.

25 25 is a fork-shaped projection on the underside of the member 20; it is adapted to receive in its fork the upper edge of the inserted coin 26.

20 When the safe is closed after insertion of a coin 26, the horizontal arm 12' of the bell crank lever 12 is raised owing to the pin 13 coming in contact with the back plate 1, and 25 the coin 26 resting on it is pressed against the member 20, whereby the parts of the said member are swung upward out of the line of support drawn through the projection 22 and the end of the bolt arm 18. In this 30 movement the pin 18⁴ shifts slightly in the slot 18³. This "play" between the two parts prevents the member 20 from swinging out too far. In this partially swung out position the member 20 does not offer any 35 resistance to the movement of the lock bolt, and the safe can then be locked. By the locking movement the parts of the member are swung still farther outward and at the same time the coin 26 is brought into a 40 slanting position (Fig. 5) by the forked projection 23, which moves simultaneously and thus causes the coin to fall. The coin falls into a funnel 27, under the mouth of which is the coin slot 28', fitted on the in- 45 side with a spring flap 28² of a money box 28, the hinged cover of which can be locked by means of a lock 29.

50 The money box 28 is placed in the compartment formed in the casing of the safe and is held therein by the bolt 30' of a lock 30 fitted on the money box or on the wall of the safe. The money box 28 can be removed from the safe after unlocking the lock 30, but its contents, however, are only accessible 55 after the second lock 29 has been opened.

55 The construction of the money box and the locking of same in the safe, do not form any part of the invention. In drawing back the bolt lock the member 20 is returned by 60 the spring 24 into the position in which it stops the lock bolt.

65 In the bolt stopping mechanism shown in Figs. 6 and 7, the member 20 is formed in one piece, is actuated by the spring 24 and is hinged at 21 on the bolt arm 18. In the

unlocked position of the lock bolt the free end of the member 20 bears against a projection 22 on the wall of the safe. On raising the lever 12, the member 20 is raised by means of the inserted coin 26 sufficiently to 70 allow of the free end of the member 20 coming above the projection 22, over which the said member slides during the locking movement of the lock bolt.

75 In the construction shown in Fig. 8 the member 20 bears with a shoulder against a projection 31 on the transverse partition 4, over which the shoulder of the member must be raised by the coin, in order to permit of the locking movement of the lock bolt. The 80 member stopping the movement of the lock bolt may also be shifted by the coin parallel to itself to such an extent as to allow of the locking movement of the lock. The herein described bolt-stopping devices may also be 85 used with vertical lock bolts and the lever for pressing the coin against the stopping member may be arranged to swing in an inclined plane, or even a horizontal plane. Instead of allowing the lever to act directly 90 on the coin, the said lever may also be coupled to a sliding part acting on the coin, or the pressing of the coin against the stopping member may also be effected alone by a 95 sliding piece.

Having now particularly described and ascertained the nature of my said invention and in what manner the same is to be performed, I declare that what I claim is:—

1. A coin controlled lock, comprising in 100 combination with a casing, a lock bolt, means removably interposed between said lock bolt and the wall of said casing to obstruct the movement of said bolt, a coin chute having a movable bottom, an element 105 carried by said interposed means and forming the top of said coin chute, and means to actuate said movable bottom against the inserted coin to move said interposed means out of the path of said lock bolt, whereby 110 the latter may be thrown to locked position.

2. A coin controlled lock, comprising in combination with a casing, a sliding lock bolt therein, removable means interposed between said lock bolt and said casing to obstruct its sliding movement, a coin chute comprising fixed sides and a movable bottom, means to actuate said bottom against a coin when the casing is closed, and means carried by said interposed means to be actuated by said coin when the latter is moved by said bottom, to remove said interposed means from the path of said sliding lock bolt, whereby the lock may be thrown to 115 locked position.

3. A coin controlled lock, comprising in combination with a casing, a sliding bolt, means interposed between the end of said lock bolt and the wall of said casing to prevent the sliding movement of said bolt, said 120

interposed means being constructed to be swung out of the path of said bolt, a coin chute located adjacent said interposed means, a movable bottom in said chute 5 adapted to lift a coin, and a device opposing said movable bottom and carried by said interposed means, whereby when said movable bottom lifts a coin, the latter will bear against said opposing device and throw said 10 interposed means out of the path of said sliding lock bolt.

4. A coin controlled lock, comprising in combination with a casing, a sliding lock bolt, a jointed element interposed in the path 15 of said sliding lock bolt between the latter and the wall of said casing, means to receive a coin, a device to lift said coin and said receiving means, an element opposing said lifting device and carried by said interposed means, whereby when said coin is 20 lifted it will bear against said opposing element and throw said interposed means out of the path of said lock bolt.

5. A coin controlled lock, comprising in combination with a casing, a sliding bolt, an element jointed to said lock bolt and bearing against the wall of said casing in the path of movement of said lock bolt, a coin chute located at one side of said interposed element, a device movable toward said interposed element through said coin chute, a device carried by said interposed element opposite said first mentioned device, and means to move the latter when the casing is 30 closed whereby the latter is adapted to bear against the inserted coin to raise said opposite device to throw the interposed element 35 out of the path of movement of said sliding lock bolt.

6. A coin controlled lock, comprising in combination with a casing, a sliding lock bolt, an element hinged to said lock bolt and bearing against the wall of said casing, in the path of movement of said bolt, a coin chute located at one side of said interposed 40 element, a rock arm forming the bottom of said chute and movable therethrough, a forked element carried by said interposed element opposite said rock arm, and means to move said rock arm toward said forked 45 element, whereby, when a coin is inserted in said chute, said interposed element may be thrown out of the path of movement of said sliding lock bolt. 50

7. In a coin controlled lock, comprising in combination with a casing, a sliding bolt, a jointed element interposed between said sliding lock bolt and the wall of said casing in the path of movement of said bolt, a coin chute located at one side of said jointed 55 element, a rock arm pivoted to form the bottom of said chute, and to be movable therein, a forked element carried by said jointed element above said chute and opposite said rock arm, and means to actuate 60 said rock arm toward said forked element, when the casing is closed, whereby when a coin is inserted in said chute, between said rock arm and said fork element, the latter will throw said jointed element out of the 65 path of movement of said sliding bolt. 70

In testimony whereof I affix my signature in presence of two witnesses.
